CLAIM

The ornamental design for a airline passenger seat back
combined LCD display and battery pack unit for an
entertainment and information system, substantially as
shown and described.

DESCRIPTION

FIG. 1 is a front perspective view of a airline passenger
seat back combined LCD display and battery pack unit
for an entertainment and information system showing
our new design;

FIG. 2 is a top plan view thereof;

FIG. 3 is a rear elevational view thereof;

FIG. 4 is a bottom plan view thereof; and,
FIG. 5 is a right side elevational view, the left side being
a mirror image thereof.

FIG. 1

FIG. 2

FIG. 3

FIG. 4

FIG. 5
